J. JOHNSON.

Shell.

No. 38,491.

Patented May 12, 1863.

John Johnson

Lemuel W. Merrill
Char. H. Smith

UNITED STATES PATENT OFFICE.

JOB JOHNSON, OF BROOKLYN, NEW YORK.

IMPROVEMENT IN EXPLOSIVE PROJECTILES.

Specification forming part of Letters Patent No. 38,191, dated May 12, 1863.

To all whom it may concern:

Be it known that I, JOB JOHNSON, of Brooklyn, in the county of Kings and State of New York, have invented and made a certain new and useful Improvement in Projectiles; and I do hereby declare the following to be a full, clear, and exact description of my said invention, reference being had to the annexed drawings, making part of this specification, wherein—

Figure 1 is a longitudinal section of my projectile. Fig. 2 is an end view of the same, and Fig. 3 is a cross-section at the line *x x*.

Similar marks of reference denote the same parts.

Projectiles have heretofore been made with a screw-cap at the rear end of a powder-chamber, and also with a circular cutting-edge at the front end, and with a cap to be exploded by concussion produced when the projectile strikes any object.

The nature of my said invention consists in a cross-bar and screw fitted in a peculiar manner to retain the cap that closes the powder-chamber, whereby the compression required between the cap and shell can be secured, and risk of premature explosion, in consequence of screwing in a cap, is avoided. I also make use of a conical end to my ball, formed with a circular notched cutting-edge, within which is a cavity, so that the conical end concentrates the inertia of the ball, when fired, on a comparatively small surface, rendering the blow much more effective than would be the case if said cutting-edge were of the diameter of the ball, or nearly so, and the said notches in the cutting-edge penetrate any article they may strike, instead of glancing off when fired at an inclination to the surface to be penetrated. I also make use of a spring-cylinder to hold on the detonating or percussion cap at the end of a screw-rod that is driven in by the concussion of the ball against the article penetrated, and causes the explosion of the shell.

In the drawings, *a* is the shell. *b* is the conical end thereof. *c* is the notched cutting-edge around the cavity *d*, for the purpose of penetrating the article struck by the ball, in consequence of the diminished area against which the inertia of the ball acts, and there is no point to be broken off by a blow against iron armor, as is the case with the ordinary

projectiles, and the notching of said cutting-edge *c* prevents the projectile glancing off when striking the article at an inclination.

e is the powder-chamber, and *f* is a cap fitted to the rear end thereof. The rear end of this powder-chamber has an interior flange, *u*, in which are notches *h h*, to pass the ends of the cross-bar *g*, that is attached to the spindle *k*, and by it can be turned, after it is passed through the said notches *h*, until one end of said cross-bar is arrested by the lug *i*.

In order to draw upon the spindle *k* and press the cap *f* to the end of the shell, I employ the nut *l* and a screw-thread cut on the said spindle *k*, near the outer end thereof. A head, *m*, is provided to said spindle *k*, and a washer, *n*, of zinc or soft metal, is introduced between the nut *l* and cap *f* prior to the attaching of the cross-bar *g*, which is done by riveting the same firmly upon the end of *k*. When the nut *l* is unscrewed, the bar *g* is relieved, so that it can turn with the spindle *k*, but the nut *l* cannot be entirely detached from the head *m*, and when unscrewed back against said head the parts bind together sufficiently to allow the spindle and cross-bar to be turned in its loose condition by means of said nut; but when said cross-bar is entered at the rear end of the bomb and rotated until one end of said cross-bar comes against the block *i*, the same is stopped, and the nut *l* can be screwed up tight against the rear end of the cap *f*, effectually binding the same in place, and the washer *n*, of soft metal, effectually prevents the fire of the explosion penetrating the chamber *e*. This chamber *e* is to be filled with powder at any time previous to or during an action.

In the rear end of the shell *a*, I form holes, as at *p*, and cast a ring of lead or other soft metal, *o*, in a suitable mold, and surrounding the cap *f*. This ring *o*, being slightly larger than the projectile, and being spread by the force of the explosion, takes the interior of the gun, whether rifled or plain; and the holes *p p p* being irregular, as shown by dotted lines in Fig. 3, the said cap *f* cannot be placed other than in a correct position.

g is a rod screwed in at *t* from the front end of the ball, and reaching to within a short distance of the back end of the chamber *e*. This rod carries at the back end the percussion-cap *s*, that is held upon the rod by a cylindrical spring *r*, formed of a piece of sheet metal rolled

up, the ends not being attached, in order that the same may spring over the percussion-cap and rod *q* and hold the same to its place and prevent the cap shaking off in transportation.

In the conical part *b* of my shell I provide grooves, as at *e e*, to give or aid in giving rotation to the ball *a*, fired in consequence of the inclined position of said grooves.

What I claim, and desire to secure by Letters Patent, is—

1. The cross-bar *g*, screw-spindle *k*, and internal flange, *u*, in combination with the cap *t*, nut *l*, and soft-metal ring *o*, fitted and act-

ing in the manner and for the purposes set forth.

2. The spring-tube *r*, to hold on the detonating cap *s*, in combination with the rod *q* and screw *t*, that is driven in by the concussion, as set forth.

In witness whereof I have hereunto set my signature this 4th day of November, 1862.

JOB JOHNSON.

Witnesses:

CHAS. H. SMITH,

LEMU^EL W. SERRELL.
